DISPLAY COUNTER

Bertrand R. Walsh, Forest Hills, N. Y.

Application October 8, 1949, Serial No. 5,391

Term of patent 3½ years

(Cl. D80—2)

To all whom it may concern:

Be it known that I, Bertrand R. Walsh, a citizen of the United States of America, residing at Forest Hills, in the county of Queens and State of New York, have invented a new, original, and ornamental Design for Display Counter, of which the following is a specification, reference being had to the accompanying drawing, forming part thereof.

Fig. 1 is a front perspective view of a display counter, showing my new design;

Fig. 2 is a side elevational view;

Fig. 3 is a rear elevational view;

Fig. 4 is a front elevational view in collapsed position; and

Fig. 5 is a side elevational view in collapsed position.

I claim:

The ornamental design for a display counter, substantially as shown.

BERTRAND R. WALSH.
